PREPARATION OF LIGHT-COLORED FRESH
FRUIT FOR MARKET

Charles D. Cothran, Pomona, Calif., assignor, by
mesne assignments, to Brogdex Company, a
corporation of California

No Drawing. Application July 24, 1941,
Serial No. 403,901

6 Claims. (Cl. 99—103)

This invention relates to preparation of light-colored fresh fruit for market; and it relates more particularly to improvements in the practice of providing lemons, which have a rind of predominantly yellow or yellowish color and are commercially classified, when ready for shipment to market, into various quality grades in which the particular shade of yellow is a vitally controlling factor, with a substantially transparent waxy coating not only suitable to perform the indispensable function of greatly retarding withering or shriveling but also of such character as to present a glossy or shiny surface produced in various known ways. The purpose of the present improvements is to prevent lemons or other light-colored fresh fruits, the commercial grading of which depends to a considerable extent upon their relative lightness or delicacy of color shade in comparison with customary trade standards, from being wrongly graded after they have been provided with such a glossy or lustrous coating of waxy material.

Although the invention can be usefully employed in handling light-colored fruit other than lemons, it is in the lemon-packing industry that the invention is of greatest present utility and importance. In explaining the principles of the invention hereinafter, therefore, reference will be made more particularly to the commercial handling of lemons by way of illustrative example, but without implying that practice of the invention is necessarily limited to this particular field.

Although a high gloss or polish has always been regarded by the trade as a definitely desirable characteristic of wax-coated oranges, an exactly opposite preference in the case of wax-coated lemons had always been manifested by the trade up to only a few years ago, and the compositions and methods employed for waxing lemons up to that time had always been such as would ensure the lemons having a relatively dull or lusterless surface when shipped to market. A few years ago, however, there developed a trade preference for wax-coated lemons having a high gloss or polish, whereupon the lemon packers and shippers were obliged to meet this changed demand and to alter their waxing methods accordingly. Up to that time, the practice of waxing, which had become well established in this country and virtually mandatory in packing all fresh citrus fruits for shipment to market, had proved thoroughly satisfactory in the lemon packing industry as well as in the orange packing industry. But after lemon

packers were obliged to modify their waxing methods somewhat in order to comply with the aforesaid changed trade demand for wax-coated lemons having a glossy instead of a relatively dull surface, lemon packers found that a larger proportion of their lemons packed out for shipment had to be classified as of lower quality than first grade fruit, on the color basis. Although the reason for this was not at all understood, lemon packers were generally inclined to charge the waxing treatment with responsibility for it, believing that the darkening of the color of the waxed lemons must be due to some adverse action of the coating material on the fruit rind causing the color to darken. Although this was not actually so, and although decrease in normal percentage of first grade fruit was in reality due to a false classification or grading not then appreciated, lemon growers and shippers suffered substantial losses from this difficulty for a long time, during which there were repeated unsuccessful efforts to remedy the difficulty.

According to the present invention, the aforesaid false classification of high grade lemons as lower grade lemons, consequent upon the stated change on lemon-waxing procedure, is effectively prevented in a simple, practical and economical manner, whereby lemon growers and shippers are saved substantial losses long regarded as inseparable from the practice of waxing lemons where a relatively high gloss or polish had to be produced.

It is a well known fact that the trade has a pronounced preference for lemons that are "true lemon yellow" in color. This designation embraces a substantial range of specific color shades or tints from pale yellow to deeper shades that are still substantially free of a pronounced reddish or coppery tint. This contrasts strikingly with the well known great desirability in the case of oranges, of relatively high coloration, as evidenced by the various expedients, such as dyeing, that are resorted to in order to obtain the ideal deep orange shades.

The official regulations established for the grading of lemons permit a certain percentage of bright yellow or fully colored fruit to be included in the first grade, provided it does not show a distinct coppery tint, or "bronzing" as it is sometimes called. A fairly pale shade of yellow is customarily regarded as characteristic of lemons in prime condition in respect to proper degree of maturity, juice content, freshness and other qualities important for edibility. Pronounced high coloration (a relatively deep or in-

tense and darker shade of yellow), if it includes reddish or coppery tinting, is regarded as indicating overmaturity and lack of freshness, as well as weakness or poor keeping quality. Owing to certain conditions and practices peculiar to the growing and marketing of lemons, especially the widespread practice of holding lemons of various degrees of maturity in storage, sometimes for months, in order to develop proper color, juice availability and other desirable characteristics before packing them out for shipment to market, it is to be expected that a rather substantial percentage (in some cases well over 50 per cent) of lemons produced will fail to meet the true lemon yellow standard set for commercial first grade lemons. No matter how carefully the temperature, humidity and other conditions of storage are controlled, more or less of the lemons undergo over-coloring or "bronzing," the extent of this depending upon many factors including local soil, climatic and other cultural conditions. But, for any given producing locality, the percentage of lemons that should normally be packed out is rather definitely known.

Since first grade fruit naturally brings the highest price, lemon growers and shippers are vitally interested in seeing to it that as large a proportion of their lemon output as possible gets into the first or highest quality grade. Anything which decreases the proportion of their fruit normally going into the first grade and causes a larger than normal proportion of it to be placed in a lower grade, is therefore highly objectionable and to be avoided so far as possible because of the resultant serious reduction in profits.

The separation of lemons into the commercially recognized shipping grades occurs as the last step of their handling through the packing house at the locality of production, just before they are actually placed in the shipping crates or boxes in which they are transported to market. In this final grading or sorting, the lemons are separated according to surface appearance, taking into account the different shades and uniformity of yellow coloration, as well as rind texture and the presence or absence of surface injuries, into established commercial marketing grades. Usually these grades are first, second and standard. The grading is done by expert graders who, through long experience and constant practice, are able to distinguish accurately at a glance, and pick out, these several recognized grades as the lemons are carried past them in a continuous stream resting on the grading belt to which the lemons are delivered from preceding packing operations. Only fruit of the best quality is selected for the first grade; that is, fruit of substantially uniform coloration within the range of shades included in true lemon yellow, and having a smooth fine-textured rind practically free from surface blemish. Second grade fruit is so classified either because it is less perfect in respect to rind texture and freedom from blemish, or because it is more mature as indicated by its higher or deeper yellow coloration showing some reddish or coppery tints, or for both these reasons. "Standards" are merchantable lemons, most of which are usually still more highly colored and more bronzed, this grade also including scarred fruit and fruit which, as indicated by high coloration or otherwise, is obviously weak. Lemons that are so defective as not to qualify for any of these commercial shipping grades are picked out as "culls" and discarded or otherwise suitably disposed of. Where the standard of grading of the

lemons is lowered to include more than the permissible small proportion of relatively highly colored fruit in the first grade, a shipment of such "first grade" lemons is likely to be seriously penalized upon arrival and inspection at the marketing destination. This is because the shipment as a whole is likely to be officially reported as "red," "bronze," "aged," or otherwise designated as inferior in marketing quality, and hence to sell only at a substantial price concession; this, in spite of the fact that nearly all or much the greater part of the fruit in the shipment is actually perfectly sound and first grade. The risk of incurring such a penalty therefore impels most lemon packers and shippers to err on the side of safety by putting all doubtful fruit into the second grade.

For nearly twenty years, it has been regular established practice, in preparing lemons and other citrus fruits for shipment to market from the locality of production, to provide them with a transparent protective coating of wax or waxy composition, so extremely thin as to be almost imperceptible but, when properly applied, effective to reduce considerably the loss of moisture through the skin or rind normally suffered by unprotected lemons while they are being prepared for market and distributed to the trade and to ultimate consumers. In some cases the coating is applied to the lemons only just before final grading and shipment; in others, it is applied also prior to storing or "curing" them. This is especially necessary where, as is usual whether or not they are to be stored, the lemons brought in from the groves are subjected to a thorough cleansing with warm water usually containing soda ash and frequently other additions such as soap, solvents derived from petroleum, or other cleansing aids, in order to remove dust, oily soot, insect deposits and foreign matter of all kinds. Such cleansing treatment also commonly removes some of the natural oily and waxy constituents of the rind or peel, thus tending to deprive the fruit to some extent of its natural protection against withering or shrinkage and to accelerate the rate at which this can normally be expected to occur in un-washed fruit. By properly applying a very thin coating of suitable waxy material in ways now well known to those skilled in the art, it has long been feasible not only to offset this increase in rate of shrinkage, but also to go much farther and to reduce the rate of shrinkage to one-half or less of that which is normal to fruit even in its natural or untreated condition. Because the fruit is thereby effectively maintained firm, plump and in generally fine fresh condition throughout the period of shipment, distribution and delivery through the ordinary trade channels and into the hands of the ultimate consumer, the practice of providing it with a waxy protective coating has proved highly beneficial to growers and shippers and, in the citrus fruit industry especially, has been so universally adopted as long since to have become virtually mandatory practice in packing lemons as well as oranges.

For a long time after it became regular commercial practice to protectively wax-coat lemons, lemon packers were quite as thoroughly pleased and satisfied with the results of the practice as have been packers of oranges. The compositions and methods most commonly employed for waxing lemons were certain of those disclosed, for example, in the patents to Brogden 1,585,371 and Trowbridge and Cothran 2,196,164; the waxy material employed being paraffin, with which was usually admixed an oil of the "Nujol" type.

Throughout this long period, the compositions used and the ways of applying them to the lemons were such as to leave the coated lemons with a relatively dull or lusterless surface. But, after the practice was changed in order to satisfy the new trade demand for wax-coated lemons having higher luster, it was not long before large packers and shippers of lemons began to complain that a greater than normally to be expected proportion of their waxed lemons were showing, at the time of final grading and packing into boxes for shipment to market, too deep or high a yellow coloration to permit classifying such lemons as first grade fruit. In the absence of any other explanation to account for this, and since comparative tests appeared to indicate that when the same lemons were not waxed the aforesaid difficulty did not arise, it was supposed that the waxy material being used must have some undesirable action on the lemon rind, perhaps causing a pigmentary change of some kind that was responsible for the objectionable deeper coloration. This seemed plausible, more especially in the case of those lemons which, in addition to being given, as required by the new practice, a "high polish" waxing at the time they were packed out for shipment, had also received an application of wax before being placed in storage, to hold the fruit plump during the storage period, a procedure that had formerly been and continued to be common. The fact that a large proportion of the California lemon crop is customarily stored for a substantial time before packing and shipment, therefore rendered the problem all the more serious. Against the view that there was some adverse action of the coating material on the lemon rind pigments, was the consideration that the wax coating compositions employed after the change in practice were, at least in some cases, the same waxy compositions that had been previously used on lemons for years with such complete success and satisfaction.

Although it was thus highly doubtful that the observed deepening in coloration was due to action of the waxy material causing pigmentary change, lemon packers were faced with the fact that, whatever the reason might be, the application of a waxy coating was apparently responsible for their being unable to pack but as large a proportion of first grade lemons as formerly. Yet they were obliged to continue the waxing practice because, admittedly, it was indispensable for keeping lemons firm, plump and unwithered throughout the period of shipment, wholesale marketing and retail distribution to consumers. The objectionable effect upon coloration was simply recognized and hence accepted as a serious disadvantage inherent in the nevertheless indispensable waxing of lemons for which there appeared to be no remedy notwithstanding persistent efforts to find one.

In the course of extensive investigation conducted in the hope of solving this troublesome problem confronting lemon packers, the present applicant discovered that the observed relative darkening or deepening of the yellow coloration of waxed lemons as compared to unwaxed lemons, noted only after lemons had been commercially waxed for years without any such objectionable effect being produced, was not real in the sense of being a change in the color of the lemons themselves, but was only apparent; also that it was due to a previously wholly unsuspected cause arising out of the aforesaid change in lemon packing practice. That is, it was due to taking

steps, just prior to final grading and shipment of the lemons, to ensure their having a high polish, gloss or shine.

Under the former practice, it had been generally customary, as explained hereinabove, to apply to lemons a coating composition of which the waxy component was wholly paraffin, with which was often mixed a relatively large proportion of white mineral oil such as "Nujoil." Moreover, the 5 coated lemons were subjected to only the minimum amount of rubbing on soft horsehair brush rolls that would suffice to spread the coating material out uniformly in a thin film. In the absence of vigorous and somewhat prolonged brushing, a coating of relatively soft and low-melting waxy material such as paraffin does not acquire a pronounced polish or shine, much less when a considerable proportion of a non-volatile oil is mixed therewith. However, with the advent of 10 the trade demand for a high polish on lemons, relatively prolonged and vigorous brushing of wax-coated lemons just prior to final grading and shipment became and still is common practice, this being effective to markedly enhance surface 15 gloss or shine whether the wax is applied at this final stage only, or before storage of the lemons, or at both stages. Under the changed practice, 20 oil is either no longer used with the paraffin in the final "high polish" treatment, or else it is used in much smaller proportion than under the former practice. In addition, the paraffin is often replaced in part by a harder and higher-melting wax such as carnauba, that will enable attainment of a much better polish. In order still further to enhance the shine or polish on the lemons, the rubbing or brushing of the coated fruit 25 is frequently conducted in a heated atmosphere, in accordance with the processes disclosed in such patents as Brogden 1,641,112 and Brogden and Trowbridge 1,940,530, which had not been used commercially for waxing lemons prior to the trade demand that they be given a high luster or polish. Sometimes, in order to avoid extensive brushing or the use of heat, or both, the lemons 30 are simply dipped in or sprayed with emulsions of waxy material that includes carnauba wax in addition to paraffin but is unaccompanied by non-volatile oil, the coating thus applied possessing, 35 merely upon drying and without rubbing or brushing, the desired degree of luster or polish. Emulsions of this "dry bright" type are disclosed in the aforesaid patent to Trowbridge and Cothran 2,196,164, but were not employed in commercially waxing lemons until "high polish" treatment 40 of lemons became necessary because of trade demand.

The "high polish" waxing treatment to which lemons have been quite generally subjected since the aforesaid change in practice went into effect, 45 occurs just prior to the above-described final grading of the fruit into "firsts," "seconds" and "standards," immediately preceding boxing and shipment to market. But both prior to and since said change in practice, it has been generally customary also to give the lemons a preliminary coating of wax, after they have been received from the grove and cleansed, and before putting them in storage to cure and develop color to the desired extent, a practice to which brief reference has already been made hereinabove. A 50 waxing treatment preceding storage aids greatly in maintaining the lemons firm and plump during the storage period, which is often a matter of months, but there is no necessity at this stage of 55 lemon handling to give the fruit a high surface

luster or polish, and it is still not the practice to do so.

After investigating at great length, without useful result, a number of possible causes of the trouble, such as the possibility that the waxy materials employed, including those added to enhance the luster or polish, might act upon the rind to produce a pigmentary change resulting in deeper coloration, or that the more extensive brushing or the use of heat might be a contributing cause, this applicant finally discovered that the explanation lay not in any deepening of the actual rind coloration, but in an optical effect resulting from the high polish or gloss on the outer or exposed surface of the transparent waxy layer encasing the lemons, whereby lemons whose rind is actually of a yellow shade included within the color range permissible for the first grade lemons, but in the deeper-tinted portion of said range, are caused to appear more highly colored than they actually are and than is acceptable for first grade fruit. As a consequence, most of such lemons, which may be termed border-line first grade fruit and which are actually of first grade quality in every respect, were being regularly allocated to second grade by the graders, as would be expected, thus accounting for the observed abnormally low pack-out of first grade fruit.

The true causes of the difficulty having thus been discovered to be apparently a matter of light reflectance, applicant then found that it could be remedied by imparting in any suitable manner to the glossy transparent waxy coating of the lemons a tint within the blue-green range sufficient to correct or compensate for the apparent lowering of the color grade, thereby restoring the appearance of the fruit, so far as concerns degree of rind coloration, to what it was before the lustrous coating was applied. By carefully adjusting and controlling the degree to which the coating is tinted, the desired effect can be produced without the tinting itself being noticeable upon inspection of the fruit. The effect is to neutralize or correct the cause, whatever it may be, formerly responsible for the failure of the actual color of the lemon to be transmitted through and from the glossy waxy coating to the eye of an observer. Employment of the invention in practice has now demonstrated that this simple expedient provides a completely satisfactory solution of the problem which for some years had proved so troublesome and expensive to packers.

In practice, a simple and effective way to accomplish the corrective tinting of the lustrous waxy coating is to incorporate with the waxy material thereof (a wax or wax-oil composition), prior to applying the same to the fruit, the necessary very small proportion of some coloring matter, such as an oil-soluble dye, within the blue-green range that is compatible therewith, i. e., miscible with or soluble in said waxy material to such an extent as substantially not to diminish the transparency of the applied waxy coating.

Without committing this applicant to any particular theory as a basis for his invention, it seems reasonable to suppose that, due to giving an uncorrected waxy coating on the lemon a high luster or polish, the total light reflectance from the surface of the lemon itself, through and from the transparent waxy layer, is rendered more or less deficient in those wave lengths between yellow and violet, particularly

in those wave lengths corresponding to blue and green; as compared to the total light reflectance from the surface of the same lemon either un-waxed or provided with a waxy coating that is much less lustrous. Whether this is due to light dispersion or absorption, or both, and whether or not the curvature of the surfaces concerned also enters into the matter, there is in any event an apparent deepening or bronzing of the natural yellow of the lemon by reason of the relatively greater proportion of the longer orange and red wave lengths in the total light reflected from the surface of the lemon when its wax-coating is highly burnished or glossy. Consequently, if the actual color of the lemon has developed to a point where its shade of yellow approaches but does not exceed the minimum depth or intensity permissible for including it in first grade fruit, and if that lemon be then provided with an uncorrected waxy coating having a high luster or polish, the lemon will appear to the grader to be higher colored and of a more intense or deeper yellow shade than is permissible in first grade lemons. The grader will accordingly put it into the second grade in spite of the fact that it is actually a first grade lemon. But coloring the waxy coating by means of a dye within the blue-green range, in accordance with the principles of the invention, makes up or compensates for the aforesaid deficiency of the total light reflectance in respect to wave lengths between yellow and violet. Therefore, both to the grader in the packing house, as well as to the inspector at the marketing destination to which it is shipped, such a lemon then appears to be, as it actually is, a first grade lemon.

Typical oil-soluble dyes suitable for use in practicing the invention are: "National D and C Green #6" (otherwise known as "Quinazarine Green SS"), "Oil Green Q261," "Oil Blue 1800," "Oil Blue B Base," "Oil Blue Green" and "Oil Green Q Base." All these dyes are obtainable from National Aniline and Chemical Company under the names indicated. Use of the first mentioned dye, National D and C Green #6 (Quinazarine Green SS), in practicing the invention is consistent with the present official requirements under the Pure Food and Drug Act.

The proportion of dye necessary to employ in the waxy coating in order to effect the desired correction for apparently deepened rind coloration due to the gloss or shine is relatively minute, being in any event only a small fraction of one per cent by weight of the waxy material (wax, or wax plus non-volatile oil) used for the protective coating. Less than 1 part of dye to 5000 parts of waxy material is ordinarily not likely to produce useful results, while it is practically never necessary to use a larger proportion of dye than 1 part to 1500 parts of waxy material. A proportion range of from 1:3500 to 1:2500 represents typical good practice. This is insufficient to give more than a mere trace of dye in the coating on a lemon, and there is no dyeing of the lemon rind or peel itself. Thus, assuming that the proportion of dye to waxy material is 1:3000, the protective coating on a single lemon carries on the order of about 0.06 milligram of dye, in a typical instance. This gives the transparent glossy waxy coating a greenish or bluish green cast which may be so slight as to be quite unnoticeable but which is effective, probably at least in part as a light screen or filter, to accomplish the correction.

whereby it becomes possible for the eye to perceive the true yellow coloration of the fruit rind.

Where the lustrous protective coating of waxy material is to be produced by atomizing or fogging said material in molten condition into contact with lemons, following the general procedure described, for example, in the aforesaid patents to Brogden 1,641,112 or Brogden and Trowbridge 1,940,530, the required minute proportion of suitable green or blue-green dye may simply be mixed with the molten waxy material in the proportion of 1:3000, for example, and thus dissolved therein, the colored molten waxy material then being atomized in contact with the lemons as they pass over revolving polisher brushes in a heated chamber, in the manner described in said patents. The waxy material may consist, for example, of a mixture of 90 parts of paraffin wax and 10 parts of a non-volatile mineral oil such as a good grade of white or medicinal oil. Where the brushing of the lemons is sufficiently vigorous and prolonged, a good polish or gloss is obtainable even where as much as 25 parts of the white mineral oil are mixed with 75 parts of paraffin. Using 1 part of National Anilin D and C Green #6 to from 2000 to 2500 parts of such a wax-oil mixture gives good results. A somewhat higher polish is obtainable where the mineral oil is entirely omitted, especially where a portion of the paraffin is replaced by carnauba wax. Thus, where the molten wax material atomized or fogged upon the lemons as they pass over the polisher brushes consists of 99 parts paraffin and 1 part carnauba wax, with no accompanying non-volatile oil, an even higher polish is obtainable, which may be still further enhanced by increasing the proportion of carnauba to as much as 5 per cent or more if desired. Where carnauba is employed as one of the waxy constituents, the slightly amber tint which it gives the coating mixture renders it advisable to use a slightly higher proportion of the green or blue-green dye than where paraffin is the only waxy component.

Where the waxy material is applied to the lemons in solution in a volatile non-aqueous solvent as is sometimes done in practice, the dye may be dissolved directly in the solvent along with the waxy material, the colored wax solution then being sprayed or atomized on the fruit, or the fruit being dipped in the solution, in the manner well understood in the art; the fruit being subsequently brushed or rubbed if necessary, after evaporation of the volatile solvent, to produce a high luster or polish.

Where the lustrous waxy coating on the lemons is obtained by application of an aqueous emulsion of the wax material, whether this be of the "dry-bright" type or of a type requiring subsequent brushing to obtain a high polish, the required minute proportion of green or blue-green dye may be incorporated with the waxy material prior to emulsification, and the emulsion applied in the usual way, with production of a green-tinted lustrous waxy coating on the lemons having substantially the same advantages as the other waxy coatings already described.

The foregoing examples are merely typical of ways in which the principles of the invention can be applied in practice in preventing false color classification or grading of lemons through the unavoidable apparent deepening of their coloration formerly resulting when providing them with protective waxy coatings having a high luster or polish. The same principles can be extended to the provisions of lustrous waxy coatings on other fresh fruits, such as grapefruit, where, in the commercial grading or classification of the fruit, a premium is or may be placed upon the lighter shades of coloration.

What is claimed is:

1. In a process of providing fruit that has a yellow rind and is customarily graded at least partly on the basis of the lightness or delicacy of its color shading, with a substantially transparent glossy protective coating of waxy material, the improvement which comprises imparting to the material of said coating a tint within the blue-green range in order to correct the apparent lowering of color grade due to the presence of said coating on the fruit.
2. In a process of providing lemons with a substantially transparent glossy protective coating of waxy material, the improvement which comprises coloring the material of said coating by means of coloring matter compatible therewith and within the blue-green range in order to correct the apparent lowering of color grade due to the presence of said coating on the fruit.
3. In a process of providing lemons with a substantially transparent glossy protective coating of waxy material, the improvement which comprises incorporating with said waxy material before its application to the lemons a sufficient small proportion of an oil-soluble dye within the blue-green range to correct the apparent lowering of color grade due to the presence of said coating on the fruit.
4. In the art of preparing for market fresh fruit that has a yellow rind and is customarily graded at least partly on the basis of the lightness or delicacy of its color shading, the method which comprises providing such fruit with a glossy transparent protective coating of waxy material having a tint within the blue-green range, and then color-grading the fruit.
5. In the art of preparing lemons for market, the method which comprises providing lemons with a glossy transparent protective coating of waxy material colored by means of coloring matter compatible therewith and within the blue-green range, and then color-grading the wax-coated lemons.
6. In the art of preparing lemons for market, the method which comprises providing lemons with a glossy transparent protective coating of waxy material having incorporated therewith a minute proportion of an oil-soluble dye within the blue-green range, and then color-grading the wax-coated lemons.

CHARLES D. COTHRAN.
